UNITED STATES PATENT OFFICE.

CARL LYNNOCK, OF DENVER, COLORADO, ASSIGNOR, BY MESNE ASSIGNMENTS, TO MODERN SALES BUREAU, OF CHICAGO, ILLINOIS, A CORPORATION OF ILLINOIS.

ENGINE-STARTER FOR AUTOMOBILES.

1,090,637.

Specification of Letters Patent. Patented Mar. 17, 1914.

Application filed September 18, 1911. Serial No. 649,802.

To all whom it may concern:

Be it known that I, CARL LYNNOCK, a citizen of the United States, residing in the city and county of Denver and State of Colorado, have invented certain new and useful Improvements in Engine-Starters for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for starting internal combustion engines of automobiles, my object being to provide a starting device adapted to be operated by the chauffeur without leaving his position in the machine.

My further object is to provide a device of this character which shall be easily actuated, and which shall efficiently perform the engine-starting function, and which, after the starting function has been performed, will automatically detach itself from the engine shaft.

In carrying out my improvement, I employ a clutch pulley located directly in front of the free extremity of the engine shaft and so arranged that, when the said pulley is actuated, clutch members will be arranged to interlock with the adjacent extremity of the engine shaft for the purpose of rotating the latter to start the engine. For this purpose, a cable is connected with the said pulley and leads to one member of a double cone-shaped pulley, having spirally-arranged grooves. A cable connected with the opposite member of the last-named pulley leads to a power carriage, with which a flexible device, to be directly actuated by the chauffeur, is attached. The double cone-shaped pulley, as well as the power carriage, is constructed to give the necessary advantage whereby only a comparatively small amount of power is required for the starting of the engine.

Having briefly outlined my improved construction, I will proceed to describe the same in detail, reference being made to the accompanying drawing, in which is illustrated an embodiment thereof.

In this drawing: Figure 1 is a top plan view of an automobile equipped with my im-

provement. Fig. 2 is a section taken through the clutch pulley arranged adjacent the engine shaft, which is shown in elevation, the parts being shown on a larger scale. Fig. 3 is a face view of the clutch pulley with the face-plate partly broken away. This is a view looking in the direction of arrow 3, Fig. 2. Fig. 4 is a perspective view of one of the dogs employed in connection with the clutch pulley for forming an interlocking connection with the engine shaft. Fig. 5 is a top plan view of the power carriage, forming a part of the mechanism, and shown on a larger scale than in Fig. 1. Fig. 6 is a section, taken on the line 6—6, Fig. 5, viewed in the direction of the arrow. Fig. 7 is a top plan view of a double cone-shaped power pulley forming a part of my improved construction and shown on a larger scale than in Fig. 1. Fig. 8 is a longitudinal section of the same pulley.

The same reference characters indicate the same parts in all the views.

Let the numeral 5 designate the framework of an automobile carrying an engine 6, having a shaft 7, whose forward extremity is equipped with pins 8. Journaled on the framework of the machine, directly in front of the engine shaft and having its axis in alinement with the axis of the shaft, is a clutch pulley 9. Within this pulley is located a spring 10, one extremity of which is connected with a spindle 12, as shown at 13, while the opposite extremity is connected, as shown at 15, with the body 14 of the pulley. The spindle passes through a journal box 16 and is secured therein in any suitable manner, as by set bolts 17 to prevent rotation during the operation of my improved starting mechanism. If, however, it is desired to start the engine by hand, the set bolts may be loosened and a crank applied to the protruding extremity 18 of the spindle, which is polygonal in cross section to receive a crank socket.

Mounted within the pulley 9, which is cored out and recessed for the purpose, is a disk 19 in which dogs 20 are journaled, each dog having a journal 21 engaging a recess 22 formed in the disk 19. One extremity of the spindle has an arm 23, adapted to project into a recess 24 formed in the body of the pulley adjacent the periphery of the disk 19, the said arm extending below a shoulder 25, formed on the pulley at the

- bottom of a recess 26, into which the journal extremity of the arm 23 extends during the starting movement of the pulley for the purpose of throwing the other arm 27 of the dog 5 outwardly to engage a pin 28 formed on the engine shaft. The disk 19 is also recessed, as shown at 29, to receive the arm 27 of the dog, which extends at right angles to the arm 23. As illustrated in the drawing, there 10 are four of these dogs 20, and, as the pulley 9 is given a partial rotation, the shoulder 26 acts upon the arm 23 of each dog to impart a partial rotation to the dog on its journal 21, said rotary action being sufficient to 15 throw the arm 27 outwardly through a slot 30 formed in a face plate 31 secured to the disk 19 and closing all of the recesses of the disk, except those in which the arms 27 are located, these recesses 29 registering 20 with the slots 30 of the face plate. The disk 19 is connected to the spindle 12 by means of a screw 32, whose head is countersunk in a recess 33 formed in the center of the disk, the shank of the screw passing through an 25 unthreaded perforation in the disk registering with a threaded opening 34 formed in the inner extremity of the spindle. By virtue of this screw, the disk 19 is connected with the spindle, but not made fast thereto. 30 The friction, however, between the disk and spindle and the connecting screw will be sufficient to allow the pulley body to move independently of the disk 19 until the shoulders 25 of the pulley have acted on the arms 35 23 of the dogs 20 to throw the arms 27 of the dogs, which normally occupy the recesses 29 in the disk, outwardly through the slots 30 in the face plate 31. The face plate 31 is secured to the disk by screws 35. As soon as 40 the independent movement of the pulley 9 has been sufficient to throw the arms 27 of the dogs outwardly, causing the said arms to interlock with the pins 28, with which the engine shaft is equipped, the disk 19 will 45 move with the pulley 9 sufficiently to start the engine, and, during this operation, the spring 10 will be placed under tension. As soon as the engine is started and the power on the pulley for actuating the latter has 50 ceased to act, the recoil of the spring 10 will reverse the action of the pulley, and the wall 36 of the recess 24 will act on the arm 23 to return the dog to its normal position, whereby the arm 27 is caused to reenter its recess 55 29, after which the pulley and disk 19 will move together until the actuating cable 37 is rewound upon the pulley.
- As illustrated in the drawing, the cable 37 passes from the pulley 9 to a cone pulley member 38, to which it is secured at one extremity, as shown at 39. This pulley member is spirally grooved and the connection 39 is made at the base or largest part of the pulley member, and, as the cable 37 is 60 actuated, it follows the spiral groove 40 of

the pulley member 38, the circumferential length of the groove diminishing toward the small end of the pulley member. A second cable 41 is connected with a cone pulley member 42, as shown at 43, connection also 70 being made at the base or largest diameter of the cone pulley member, the cable being normally wound upon the member 42 from its point of connection to its small extremity.

The two cone pulley members 38 and 42 are connected by a spiral spring 44 located within a recess 45 formed in the two pulley members. One extremity of this spring is connected with the member 38, as shown at 46, while the other extremity is connected with the member 42, as shown at 47. The strength of the spring 44 is such that, under normal conditions, the two pulley members 38 and 42 are virtually an integral device. 80 In the event, however, that the engine should "kick", or reverse, under the influence of a premature explosion, the pulley member 38, which, during the starting operation, is connected with the engine shaft through the medium of the cable 37 and the pulley 9 and its connections, would yield sufficiently, by virtue of the spring connection between the two cone pulley members, to prevent injury to the mechanism. 90

The cable 41 passes from the cone pulley member 42 to a drum 48, being secured thereto, as shown at 49. This drum is formed integral with a gear 50 and two relatively small drums 51, the entire structure being journaled on a shaft 52, the latter having its extremities mounted in parallel frame members 53, suitably spaced and carried by sleeves 54 slidably mounted on rods 55, whose extremities are secured to end 100 frame bars 56 and 57, mounted on the framework of the machine. The gear 50 meshes with a smaller gear 58 fast on a drum 59, the gear and drum being journaled on a shaft 60, whose extremities are also 105 mounted in the parallel frame members 53. To each of the small drums 51 is secured, as shown at 61, one extremity of a cable 62, the opposite extremities of the said cables being made fast to the end bar 56, as shown 110 at 64. Mounted on the rods 55 between the slideable sleeves 54 and the end bar 56 are spiral springs 65. A flexible operating member 66 is connected with the drum 59 at one extremity, its opposite extremity extending upwardly and terminating in a hand piece 67 within reach of the chauffeur, the said flexible device passing through an opening 68 formed in the foot board 69, the hand piece 67 forming a stop to prevent the flexible operating member 66 from moving out of the reach of the person in charge of the machine.

It is impossible to exercise a direct pull on the cord 41 for the reason that it is neces- 130

sary to have gears of varying diameter in connection with the drum 48, in order to produce sufficient force to start the engine and at the same time place the springs 65 under tension. Furthermore, the movement which places these springs 65 under tension also gives an added pull to the cable 41 and when the tension of the said springs is released, the operating strap 66 is rewound 10 and the carriage returned to its starting position by the expanding of the springs.

The mechanism just described and slidably mounted upon the bars 55 is herein referred to in its entirety as a power carriage and will be so designated in the claims.

Assuming now that the structure is installed upon an automobile, as indicated in Fig. 1 of the drawing, if it is desired to 20 start the engine, the chauffeur will grasp the hand piece 67 and pull forwardly on the flexible device 66, which will cause the drum 59 and the gear 58 to rotate on the shaft 60. The rotary action of the gear 58, 25 meshing with the gear 50, imparts a corresponding movement to the latter, and in such a direction as to wind up the cable 41 on the drum 48 and wind the cable 62 on the small drum 51. During this operation, 30 the sleeves 54 of the power carriage are caused to move rearwardly, compressing the spring 65, both the sliding movement of the carriage and the rotary action of the drum 48 serving to pull on the cable 41 and the 35 latter acting on the double cone pulley to rotate the latter by unwinding the cable 41 from the cone pulley member 42 and winding up the cable 37 on the cone pulley member 38, whereby the clutch pulley 9 is rotated to throw the arms 27 of the dogs 20 out of the disk 19 and through the slots 30 of the face plate 31 into the path of the pins 28 carried by the engine shaft, whereby the latter is rotated sufficiently for starting purposes. 40 As soon as the starting operation is complete, and the power acting on the flexible device 66 ceases to act, the recoil of the spring 10 will reverse the action of the pulley 9 and return the dogs to their normal 45 position within the disk 19, the pulley and disk being returned to their normal position and the cable 37 being wound thereon ready for the next starting operation.

Having thus described my invention, what 50 I claim is:

1. In an engine starter for automobiles, the combination with the engine shaft, and a stationary spindle located adjacent said shaft, of a pulley journaled on the said 55 spindle, a member mounted in the pulley and also adapted to turn on the spindle, a coil spring having one extremity connected with the spindle and its opposite extremity with the pulley, dogs carried by the said 60 member and protruding into recesses in the

pulley, each dog having arms projecting at right angles to each other, one arm being arranged to be operated on by the pulley to throw the other arm out of the pulley into interlocking relation with the engine shaft, 70 the pulley and said member rotating in harmony after the dogs are interlocked with the engine shaft, and a suitable connection with the said pulley for operating the latter, substantially as described.

2. The combination with the engine shaft, of a pulley normally free from the engine shaft and equipped with dogs, each dog having arms projecting at right angles to each other, and one of said arms arranged to be thrown out of the pulley into interlocking arrangement with the shaft by the rotation of the pulley, a spring connected with the pulley to be placed under tension by such movement, and a flexible device connected with the pulley for operating the latter, substantially as described.

3. The combination with an engine shaft, of a stationary spindle arranged adjacent the engine shaft, a pulley journaled on the spindle and carrying a disk which the pulley is recessed to receive, dogs journaled in the pulley and disk and comprising a part having arms projecting from opposite extremities thereof, one arm projecting into a recess formed in the pulley, the pulley being movable on the spindle independently of the disk sufficiently to act upon one arm of the dog to throw the other arm outwardly to interlocking engagement with the engine shaft, after which the pulley and disk rotate in harmony, a spring connection between the pulley and spindle, whereby the spring is placed under tension by the movement of the pulley to operate the engine shaft, and a flexible connection with the pulley for operating purposes, substantially as described.

4. The combination with an engine shaft, equipped with projections, and a stationary spindle arranged adjacent the engine shaft, of a pulley journaled to move freely on the spindle and carrying a disk also movable on the spindle, but with more friction than the pulley, dogs carried by the pulley and disk and having arms normally concealed, one of the arms projecting into a recess formed in the pulley and arranged to be acted on by the pulley to operate the dog by the movement of the pulley in either direction, the 110 dog having an arm arranged to be thrown out of the pulley into interlocking engagement with the pins on the engine shaft by the movement of the pulley in one direction, and an operative connection with the pulley 115 extending to a suitable position on the machine, substantially as described.

5. The combination with the engine shaft, of a stationary spindle located adjacent the engine shaft, a pulley journaled on the 120

spindle and freely movable, a disk carried by the pulley and connected with the spindle, to move thereon, but with greater friction than the pulley, and dogs carried by the pulley and disk and operable by the movement of the pulley independently of the disk to interlock with the engine shaft, a spring connection between the pulley and the stationary spindle, and an operative connection with the pulley for rotating the latter and starting the engine, substantially as described.

6. The combination with an engine shaft, of a clutch pulley mounted adjacent the engine shaft and arranged to interlock with the shaft when rotated, a drum composed of two members, a spring connecting the two members to cause them to operate normally as a single device, a cable member leading from the clutch pulley to one member of the drum, a second cable leading from the other member of the drum, and means for applying power to the second cable to unwind it from the said drum while the first cable is wound from the pulley upon the drum, substantially as described.

7. The combination with an engine shaft, of a clutch pulley mounted adjacent the engine shaft and arranged to interlock therewith when the pulley is rotated, a drum composed of two members spring connected to normally operate as a single device, a cable connecting the clutch pulley with one of the drum members, means adapted to be operated manually for generating power and a cable connecting the other drum member in operative relation with the said means for engine starting purposes, substantially as described.

40 8. The combination with an engine shaft, of a clutch pulley mounted adjacent the engine shaft and arranged to interlock with the latter when the pulley is rotated, a drum located in suitable proximity to the said pulley and composed of two spirally-grooved cone-shaped members spring connected to normally operate as a single device, a cable connecting the clutch pulley with one member of the drum, means for applying power for engine starting purposes, and another cable connecting the power applying means with the other member of the drum, the cable connections with the drum being such that, as the power applying means is actuated, the cable connected therewith is unwound from one member of the drum, while the cable connected with the clutch pulley is unwound from the pulley and wound on the other member of the drum.

60 9. The combination with an engine shaft, of a clutch member normally free from the engine shaft, but arranged to interlock therewith when the said member is rotated, a cable connected with the clutch member, a power carriage with which the cable is also

connected, the said carriage comprising a drum with which one extremity of the cable connected with the clutch member is secured, a gear rotating with the drum, a second gear meshing with the first-named gear, a second drum connected to rotate with the second gear, means connected with the second drum for rotating the latter, auxiliary drums rotating in harmony with the first-named gear, cables connecting the auxiliary drums with a stationary member, stationary rods suitably separated, sleeves slidable on said rods, the aforesaid drums and gearing being carried by the said sleeves, and springs interposed between the said sleeves and a stationary part whereby, as the power carriage is actuated to operate the clutch member, the springs are compressed, substantially as described.

10. The combination with an engine shaft, of a clutch member located adjacent the engine shaft and arranged to interlock therewith when the said member is rotated, a cable connected with the clutch member, a power carriage for operating the clutch member, springs placed under tension by the sliding movement of the carriage, the said carriage including a drum mounted to rotate and connected with the cable leading from the clutch member, a gear rotating with the said drum, a second gear meshing with the first-named gear, a second drum rotating with the second gear, means connected with the second drum for operating the power mechanism, auxiliary drums rotating in harmony with the first-named drum and gear, cables connecting the auxiliary drums with a stationary member, the parts being so arranged and connected that, as power is applied to the second drum, the carriage mechanism is operated to wind the cables on the auxiliary drums and the clutch member cable on the first-named drum, the carriage being actuated to place the said springs under tension, substantially as described.

11. The improvements herein described comprising engine starting mechanism, in combination with an operating cable connected therewith, a winding device upon which said cable is adapted to be wound, and means for actuating said winding device and for simultaneously moving said winding device bodily to cumulatively pull said cable and actuate said starting mechanism.

12. The improvements herein described comprising engine starting mechanism, in combination with an operating cable connected therewith, a winding device for winding said cable thereupon, and means for simultaneously moving said winding device bodily as it winds up said cable.

13. The improvements herein described comprising an engine starting mechanism having an element to be actuated, in combination with a rotary member having a ro-

5 tary movement about its axis and a bodily movement, a cable connected to said starting mechanism and said rotary element, and means for simultaneously actuating said rotary element bodily and rotatably to wind the cable thereupon and impart the resultant of its movements to said starting mechanism element.

14. In apparatus of the class described, an engine shaft and a starter connected thereto and adapted to impart rotation to said shaft, in combination with an actuating device con-

nected to said starter and embodying a member having component rotary and bodily movements, and an actuating mechanism for 15 simultaneously rotating and bodily moving said member to impart a cumulative resultant movement to said starter.

In testimony whereof I affix my signature in presence of two witnesses.

CARL LYNNOCK.
